[57] CLAIM

The ornamental design for a coat hanger organizer, as shown and described.

DESCRIPTION

FIG. 1 is a front elevational view of the coat hanger organizer showing my new design;

FIG. 2 is a rear elevational view thereof;

FIG. 3 is a right view thereof;

FIG. 4 is a left view thereof;

FIG. 5 is a top plan view thereof, the broken-line disclosure of a coat hanger being for illustrative purposes only and forming no part of the claimed design; and,

FIG. 6 is a bottom plan view thereof.
